UNITED STATES PATENT OFFICE.

WILLIAM SCOTT, OF MEDFORD, MASSACHUSETTS.

DESIGN FOR A BATH-TUB.

SPECIFICATION forming part of Design No. 23,583, dated August 21, 1894.

Application filed May 2, 1894. Serial No. 509,846. Term of patent 14 years.

To all whom it may concern:

Be it known that I, WILLIAM SCOTT, of Medford, county of Middlesex, and State of Massachusetts, have invented and produced a new and original Design for a Bath-Tub, of which the following description, in connection with the accompanying drawing, is a specification, like letters on the drawing representing like parts.

10 The bath tub embodying the design which forms the subject of my invention is shown in side elevation in the accompanying drawing, and consists of a body *a* which has the shape shown, and is provided with an outwardly projecting flange *b* near the bottom thereof, extending substantially around the periphery of said body, the said flange forming the main feature of novelty of the design. The upper surface of the said flange *b* is ornamental in shape, as shown, while the under

surface thereof is a plane horizontal surface. The plane of the said horizontal surface is at an angle to the plane of the bottom of the tub as clearly shown in the drawing, the lower surface of the portion *a²* which is below the flange sloping with relation to the said flange, the said surface forming the bottom of the tub itself. The lower surface of the flange is substantially parallel with the horizontal plane of the upper edges of the tub. 30

I claim—

The design for a bath-tub substantially as herein shown and described.

In testimony whereof I have signed my name to this specification in the presence of 35 two subscribing witnesses.

WILLIAM SCOTT.
